UNITED STATES PATENT OFFICE.

WARREN R. WALKER, OF GREAT KILLS, NEW YORK, ASSIGNOR TO COOPER HEWITT ELECTRIC COMPANY, OF HOBOKEN, NEW JERSEY, A CORPORATION OF NEW JERSEY.

MERCURY SWITCH.

Application filed May 26, 1925. Serial No. 32,970.

My present invention relates to electric switches of the liquid flow type and particularly to mercury switches. It further relates to switches of this type having a sealed envelope through which are sealed electrodes between which current path is made and broken by the movement of the mercury with relation to the other parts of the switch, and in which a perforated part or septum is positioned across the envelope between the electrodes therein which is utilized for separating the mercury in the switch into two bodies in the open circuit position thereof and which permits the joining of the said two bodies of mercury through the perforation thereof in the closed position of the switch, such septum being positioned close to the wall of the envelope throughout their adjacent portions but not sealed thereto, advantage being taken of the surface tension of the mercury to keep the mercury from flowing through the very small space between the septum and the envelope whereby is permitted the construction of a switch which is cheaply made. The invention further relates to a switch of this type in which the envelope is made of glass and the septum of the same or another vitreous material whereby, due to these parts being made separate, there is avoided the difficulties in forming the septum and the envelope unitary which result in the cracking of the switch due to unavoidable strains. The invention further relates to a switch of this type having an envelope of comparatively cheap glass and a septum which is separate therefrom and which is made of a material which is highly resistant to electric arcing.

I have discovered that a switch of this type which is adapted for making and breaking circuit therethrough either by rotation of the switch or by tilting of the switch on its axis that advantage can be taken of the natural surface tension effects of the mercury to prevent it from passing through very small passages so that a septum can be positioned in a switch but made separate therefrom due allowances being made for slight variations in size and manufacture and allowances also for changes in temperature and varying changes in temperature in the different parts due to different co-efficients of linear expansion in the materials thereof.

In the drawings, Fig. 1 is a longitudinal sectional view of an embodiment of the switch of my invention showing a sealed envelope having mercury therein and electrodes sealed thereto from either end each of which has a downward extension for contact with the mercury and one of which has a further inward longitudinal extension which carries a septum extending across said envelope and in close proximity thereto throughout the circumference thereof, said septum being provided with an aperture through which in closed circuit positions of the switch the mercury extends for making contact between said electrodes,

Fig. 2 is a transverse sectional view of the device of Fig. 1 taken along the line 2—2 and looking in the direction of the arrows in that figure,

Fig. 3 is a longitudinal sectional view of an alternative embodiment of my invention showing electrode extensions which extend around the interior of the envelope, and showing the switch in the open circuit position,

Fig. 4 is a sectional view of the device of Fig. 3 taken along line 4—4 and looking in the direction of the arrows,

Fig. 5 is a face view of an alternative form of septum having two perforations therethrough diametrically spaced,

Fig. 6 shows an alternative embodiment of the septum having one perforation which is extended arcuately for permitting the closing of the circuit during the predetermined period of time while the switch is rotating on its axis at a predetermined rate of speed and likewise be made to have the circuit open therethrough for a corresponding predetermined period of time,

Fig. 7 shows a septum having a simple perforation therethrough at one position and an arcuate perforation at another whereby the rotation of the switch in which the septum is embodied circuit may be established alternately for different periods of time when such rotation is made at a given rate of speed,

Fig. 8 shows a septum having two arcuate openings diametrically spaced whereby a similar result is produced as with the septum of Fig. 6 but in which the open circuit periods are shorter with respect to the closed circuit periods and

Fig. 9 shows a septum having an annular groove cut in the edge thereof and material wound therein such as asbestos for sealing the space between the septum and the envelope wall when such an arrangement is necessary.

In Figs. 1 and 2 of the drawing the envelope 1 preferably of borosilicate glass such as G_7O_2P glass carries sealed therethrough on each end electrode leads 2 and 3 which extend inwardly toward each other and are axially aligned. Each of the leads 2 and 3 carries an electrode 5 connected thereto which extends toward the envelope 1 wall which contact with the body of mercury 6 in the envelope, said lead 3 carries at its inner end the septum 7 of heat resisting material such as fused quartz glass or bakelite but preferably of fused quartz. Said septum 7 extends entirely across the sides between the walls of the envelope 1 and into such close relation thereto as to prevent the flow of mercury therebetween, advantage being taken of the natural surface tension of the mercury to prevent this flowing between the septum and the envelope whereby a space between septum and the envelope may be left to allow for expansion and contraction due to changes in temperature and to allow a certain degree of variation in the manufacture of the parts. Between its point of support and its edge said septum 7 has formed therethrough a perforation 8 for the flow of mercury therethrough to connect in the closed circuit position of the switch two pools into which the mercury is formed on either side of the septum 7.

In the operation of this embodiment of my invention the switch is rotated on its axis to bring said perforation 8 below or above the level of the mercury 6 for making and breaking of a current path therethrough. In its operation as a simple switch it can be rotated backward and forward to a small part to bring said opening 8 below or above the surface of the mercury as desired. In operating the device as a time switch it is rotated continuously at a predetermined rate of speed whereby the septum in travelling from its point of emerging from the mercury to its points of immersion therein occupies the predetermined period of time and likewise the movement of the opening from this point of immersion into its point of emerging from the mercury occupies the corresponding period of time, the time periods of the making and breaking of the circuit being recorded by the speed of rotation of the device. For obtaining the making of a circuit through the device at shorter intervals than that possible with the device of Fig. 1 with respect to the time periods of the opening of the circuit a septum such as shown in Fig.

5 is used where a plurality of perforations 9-9 are formed. These may be either diametrically spaced or otherwise equally spaced or they may be spaced at unequal angular distances about the center of the septum and center of rotation whereby different periods of make and break may be obtained as desired. In Fig. 6, for example, is shown the single perforation formed in the shape of an arc whereby at a given rate of speed of rotation the period of circuit make is lengthened and the period of circuit break is shortened. In Fig. 7 is shown a septum having a small perforation 9 at one point and a larger and arcuate perforation 10 at another portion whereby is obtained through the rotation of the switch intermittent periods of circuit make which are unequal in duration. And in Fig. 8 is shown two equally spaced arcuate perforations 10 in the septum 7.

The device of Figs. 1 and 2 may also be operated by tilting in which operation the perforation 8 is left in its position shown in Figs. 1 and 2 or brought to a point at a lesser depth in the mercury as desired according to the current broken and as to whether a time interval is to be injected into operation of the switch.

In Figs. 3 and 4 is shown in an open circuit position a switch similar to that of Figs. 1 and 2 with exception that electrodes 5', 5' mounted on electrode leads 2 and 3 extended circumferentially around the interior of the envelope and at a short distance therefrom whereby during the rotation of the switch for making and breaking circuit therethrough a section of each of the electrodes is at all times immersed in mercury 6 and any possible arcing between these electrodes in the mercury is precluded.

The operation of the switch of Figs. 3 and 4 is substantially the same as that of the switch in Figs. 1 and 2 and is adapted for using the septums of various sorts as has been described for the purpose of opening the intermittent makes and breaks of varying periods of time and varying alternations.

It is to be noted that in the device of my invention as has been described there is provided the switch simple of structure and mode of manufacture which can be operated without any appreciable change of center of gravity whatever, the only change being when the mercury extends through perforations and thereby slightly but unappreciably lowers the mercury level of the switch but it can be appreciated that this difference is practically insignificant.

It is to be understood that other materials than those above mentioned may be employed for the septum such as oxidized aluminum which has the property of being an insulator and at the same time has the

characteristics of high heat conductivity: Steatite, lavite, soapstones, porcelains, fire resisting clays, enameled metals, hot and cold molded compounds of the kind in which 5 bakelite, shellac, and the like are used are other materials suitable for this purpose. When desired, the switch envelope may be made of these materials with suitable insulating means for introducing the electrode.

10 I claim:

1. In a liquid flow switch, a sealed envelope, electrodes sealed through the wall of said envelope, mercury in said envelope, and an arc resisting septum positioned across the 15 envelope and separate therefrom between said electrodes, said septum being spaced away from but close enough to the envelope throughout adjacent portions to prevent the mercury from flowing therebetween, said septum being formed with an opening therethrough for connecting the said electrodes by mercury extending therethrough in a closed position of the switch.

2. In a liquid flow switch, a sealed envelope of glass, electrodes sealed through the wall of said envelope, mercury in said envelope, and an arc resisting septum positioned across the envelope and separate therefrom between said electrodes, said septum being 20 spaced away from but close enough to the envelope throughout their adjacent portions to prevent the mercury from flowing therebetween, said septum being formed with an opening therethrough for connecting the said electrodes by mercury extending therethrough in a closed position of the switch.

3. In a liquid flow switch, a sealed envelope, electrodes sealed through the wall of said envelope, mercury in said envelope, and an arc resisting septum positioned across the envelope and separate therefrom between said electrodes, said septum being spaced away from but close enough to the envelope throughout their adjacent portions to prevent the mercury from flowing therebetween yet having such a distance between them as to preclude excessive strains therebetween due to any contact through change of dimension resulting from changes of temperature 45 normal to manufacturing and operating conditions of the switch, said septum being formed with an opening therethrough for connecting the said electrodes by mercury extending therethrough in a closed position of the switch.

4. In a liquid flow switch, a sealed envelope, electrodes sealed through the wall of said envelope, mercury in said envelope, and a septum of fused quartz positioned across the envelope and separate therefrom between said electrodes and positioned close enough to the envelope throughout their adjacent portions to prevent the mercury from flowing therebetween yet having such a distance 55 between them as to preclude excessive strains

therebetween due to any contact through change of dimension resulting from changes of temperature normal to operating conditions of the switch, said septum being formed with an opening therethrough for connecting the said electrodes by mercury extending therethrough in a closed position of the switch. 70

5. In a liquid flow switch, a sealed envelope of boro-silicate glass, electrodes sealed through the wall of said envelope, mercury in said envelope and separate therefrom, and an arc resisting septum positioned across the envelope between said electrodes, said septum being spaced away from but close 80 enough to such envelope throughout their adjacent portions to prevent the mercury from flowing therebetween, said septum being formed with an opening therethrough for connecting the said electrode by mercury 85 extending therethrough in a closed position of the switch.

6. In a liquid flow switch, a sealed envelope of boro-silicate glass, electrodes sealed through the wall of said envelope, mercury in said envelope, and an arc resisting septum of vitreous material positioned across the envelope and separate therefrom between said electrodes, said septum being spaced away from but close enough to such envelope 90 throughout their adjacent portions to prevent the mercury from flowing therebetween yet having such a distance between them as to preclude excessive strains therebetween due to any contact through change of dimension resulting from changes of temperature 95 normal to operating conditions of the switch, said septum being formed with an opening therethrough for connecting the said electrodes by mercury extending therethrough in a closed position of the switch. 100

7. In a liquid flow switch, a sealed envelope of boro-silicate glass, a pair of electrodes sealed through the wall of said envelope one at each end thereof and axially aligned, mercury in said envelope, and a septum of fused quartz positioned across the envelope between said electrodes and positioned close enough to such envelope throughout their adjacent portions to prevent the mercury from flowing therebetween yet having such a distance between them as to preclude excessive strains therebetween due to any contact through change of dimension resulting from changes of temperature normal to manufacturing and operating conditions of the switch, said septum being formed with an opening therethrough for connecting the said electrodes by mercury extending therethrough in a closed position of the switch. 115

8. In an electric time switch, a sealed envelope adapted for rotation about an axis and having electrodes sealed thereinto, mercury therein, a septum extending across the envelope between the electrodes and having 120 125

a plurality of openings therethrough spaced at unequal distances with respect to said axis for joining the two spaces into which the septum divides the envelope.

5. 9. In an electric time switch, a sealed envelope having electrodes sealed thereinto, mercury therein, a septum extending across the envelope between the electrodes and having a plurality of openings therethrough 10 for joining the two spaces into which the septum divides the envelope said openings being of unequal angular extension with respect to the axis of rotation of the switch.

10. In a liquid flow switch, a sealed envelope, electrodes sealed through the wall of said envelope, mercury in said envelope, and an arc resisting septum positioned across the envelope between said electrodes a groove about its edge with packing material 20 therein to prevent the mercury from flowing therebetween, said septum being formed with an opening therethrough for connecting the said electrodes by mercury extending therethrough in a closed position of the switch.

25. 11. In a liquid flow switch, a sealed envelope, electrodes sealed through the wall of said envelope, mercury in said envelope, and an arc resisting septum positioned across the envelope between said electrodes and positioned close to such envelope and having packing material therebetween throughout their adjacent portions to prevent the mercury from flowing therebetween, said septum being formed with an opening therethrough for connecting the said electrodes by mercury extending therethrough in a 30 closed position of the switch.

35. 12. In a mercury switch in combination, a

sealed vitreous container, a septum therein and a support therefor comprising a wire 40 fixed to said septum and fixed to said container, electrodes sealed into said container and a liquid therein.

13. In a mercury switch in combination, a sealed vitreous container, mercury therein, 45 a septum therein dividing it into two chambers, means for supporting said septum in position in said container, said septum being separate from the container and spaced apart therefrom at a distance sufficient to 50 permit expansion and contraction but small enough for the surface tension of the mercury to hold the mercury against passage between said septum and the container, said switch having a passageway for the flow of 55 mercury to and from one chamber of said envelope to the other for making and breaking current path through the switch.

14. In a mercury switch, in combination, a sealed container, a septum of vitreous material therein, support for said septum comprising a wire fixed to said septum and fixed to said container, electrodes sealed into said container, and a conducting liquid therein.

15. In a mercury switch, in combination, 65 a sealed container of boro silicate glass, a septum of fused silica therein, a support for said septum comprising a wire fixed to said septum and fixed to said container, electrodes sealed into said container, and a conducting 70 liquid therein.

Signed at Hoboken, in the county of Hudson and State of New Jersey, this 21st day of May, A. D. 1925.

WARREN R. WALKER.
